[57] CLAIM

The ornamental design for a videophone, as shown and described.

DESCRIPTION

FIG. 1 is a perspective view of a combined base and handset for a video telephone with the adjustable top tilted forward showing our new design;
FIG. 2 is a front view of the base of FIG. 1;
FIG. 3 is a back view of the base of FIG. 1;
FIG. 4 is a left side view of the base of FIG. 1;
FIG. 5 is a right side view of the base of FIG. 1;
FIG. 6 is a top view of the base of FIG. 1;
FIG. 7 is a bottom view of the base of FIG. 1;
FIG. 8 is a perspective view of the handset of FIG. 1;
FIG. 9 is a perspective view of the handset of FIG. 1;
FIG. 10 is a front view of the handset of FIG. 1;
FIG. 11 is a top view of the handset of FIG. 1;
FIG. 12 is a rear view of the handset of FIG. 1;
FIG. 13 is a left side view of the handset of FIG. 1;
FIG. 14 is a right side view of the handset of FIG. 1; and,
FIG. 15 is a bottom view of the handset of FIG. 1;
The base and handset have been shown separately in FIGS. 2-15 for convenience of illustration.
